FIG 1

FIG 2

FIG. 3

FIG. 4

FIG. 1 is a frontal perspective view of the combined lamp and double grill embodying my new design with the rotatable grills angularly oriented.

FIG. 2 is an enlarged rear elevational view of the combined lamp and double grill with the rotatable grills in an aligned position.

FIG. 3 is a side elevational view thereof and,

FIG. 4 is a top plan view thereof.

The characteristic features of my design reside in the specific configuration of the combined lamp standard and double grill.

I claim:

The ornamental design for a combined lamp and double grill, as shown and described.
